UNITED STATES PATENT OFFICE.

EINER JOHNSON, OF MINNEAPOLIS, MINNESOTA.

GAS-TESTING APPARATUS.

1,074,795.

Specification of Letters Patent.

Patented Oct. 7, 1913.

Application filed December 5, 1912. Serial No. 735,072.

To all whom it may concern:

Be it known that I, EINER JOHNSON, a citizen of the United States, residing at Minneapolis, in the county of Hennepin and State of Minnesota, have invented certain new and useful Improvements in Gas-Testing Apparatus; and I do hereby declare the following to be a full, clear, and exact description of the invention, such as will enable others skilled in the art to which it appertains to make and use the same.

My invention has for its object to provide an improved apparatus especially adapted for use in determining the efficiency of a set of gas purifiers, such as are used in the manufacture of coal gas or carbureted water gas for illuminating purposes. The invention involves a novel process of obtaining this result.

In accomplishing the above result, two different methods have hitherto been employed, one of which is well known as the "gravimetric cadmium chlorid" method, and the other, also well known, as the "Tutwiler" method. The former method, while accurate, is very slow, and the latter method, while rapid, is very inaccurate. My invention combines the accuracy of the "gravimetric cadmium chlorid" method and the rapidity of the "Tutwiler" method.

The improved apparatus by which my improved method is accomplished, is illustrated in the single view of drawing which is a vertical section taken centrally through the complete apparatus.

The apparatus is preferably constructed entirely of glass and it includes the following elements: The numeral 1 indicates a bulb or main body chamber which is sealed at its lower end and contracted at its top where it is fused to a vertically extended tube 2 terminating in what is known as a Greiner and Friedrichs stop-cock 3. To the sleeve of this stop-cock are fused the lower ends of vertically extended burettes 4 and 5. These burettes 4 and 5, at their upper ends, are fitted with stoppers 6 and 7, respectively. The one side of the bulb 1, quite near to the top thereof, is fused an outwardly extended tube 8 having a stop-cock 9 interposed therein. This tube 8 has a U-shaped depression 10. The outer leg of the tube 8 terminates at 8^a, and between this point and the outer leg of the U-shaped section 10, the bulbs 11 and 12 are interposed in the said tube 8.

To the opposite side of the main bulb 1 is fused a tube 13. The inner end of this tube 13 extends downward within the main bulb 1 nearly to the bottom thereof. In the outer portion of said tube 13 is a stop-cock 14. The intermediate portion of the main bulb 1 is shown as provided with an outwardly projecting flange 15 which adapts the apparatus to be supported in an upright position by a suitable clamp, not shown, or by inserting it into a hole in a block of wood.

The apparatus may be used as follows: In making a determination from 100 to 150 cc. of a strong solution of cadmium chlorid (1.811 grams per liter) is run into the main bulb 1 from burette 4 through stop cock 3, stop-cock 9 being open, and stop-cock 14 being closed. The apparatus is then tilted into such a position that 5 or 6 cc. of the solution passes into the bulb 11 which acts as a seal and indicator, preventing traces of hydrogen sulfid from escaping unabsorbed and indicating when the cadmium chlorid solution in the main bulb 1 is nearly spent. The small bulb 12 prevents traces of the solution in the tube 8 from being carried from the apparatus. With the apparatus again in its erect position, burette 5, which is preferably graduated to read in tenths of 1 cc., is filled with a standard solution of iodin, two solutions of different iodin strengths being used, one containing .312 gram of iodin per liter and the other one-tenth as strong. The strong solution is of such a strength that 1 cc. is equivalent to .65 gram of hydrogen sulfid per 100 cubic feet. One-tenth of a cubic foot of gas is used in the determination, and is used in testing the crude gas while the working solution is used in testing partially purified gas. Stop-cock 3 is a three-way stop-cock having two oblique passages, one of which, in one position of said valve, connects the burette 4 to the tube 2, the other of which, when said stop-cock is given a half rotation, will connect the burette 5 to said tube 2. Next, the stop-cock 3 is moved to close both burettes 4 and 5 from the tube 2 and the main bulb 1 is then connected at 8^a with a gas meter while the receiving end of the tube 13 is connected with a gas supplying cock or other source of supply, as for instance, by means of a rubber tube. The meter reading being first noted, the stop-cock 14 is opened and the flow of gas so regulated that from 1 to 1.5 cubic feet per hour will pass through

the apparatus. When a color appears in the bulb 11, the gas is shut off by closing the stop-cock 14 and the meter reading is again taken to thereby note the total flow of gas.

5 In testing partly purified gas when no color has appeared in the bulb 11, after one-tenth cubic foot of gas has passed, but when a perceptible precipitate has formed in the main bulb 1, the gas supply is cut off. If a 10 perceptible precipitate has not appeared in the main bulb 1, after one-tenth of a cubic foot has passed, a flow is continued until one does appear. Next, the apparatus is directed from the meter and supply re- 15 moved from its support, the stop-cock is opened, (as shown in the drawing) and then the apparatus is so tilted that the solution in the bulb 11 runs back into the main bulb 1. Wash water is drawn in through 20 the tube 8 by applying suction at the top of the burette 4, while the stop-cock 9 is opened and the stop-cock 14 is closed, and then in the same way, by drawing in much water through the tube 13 while the stop- 25 cock 9 is closed and the stop-cock 14 is opened. The gas above the solution in the main tube 1 is removed by opening the stop-cock 9 and applying suction at the top of burette 4. Next, the stop-cock 3 is 30 closed and fresh starch solution is run into the burette 4. Then the stop-cock 3 is moved back into position shown in the drawings, and this starch solution is caused to run into the main bulb 1. Next, the 35 stop-cocks 9 and 14 are again closed and the air in the main bulb 1 is placed under diminished pressure by applying suction at the upper end of the burette 4, while the stop-cock is, of course, in the position shown 40 in the drawings. The stop-cock 3 is then again closed and the burette 4 is filled with concentrated hydro-chloric acid which is allowed to pass slowly into the main bulb 1 until the precipitated cadmium sulfid is 45 completely dissolved. A little excess of hydrochloric acid is then run into the said main bulb 1 and stop-cock 3 is then closed. The hydrogen sulfid is thus liberated in the main bulb 1, under diminished pressure 50 and out of contact with air, and the same is titrated with the iodin solution. Burette 5 is read and the iodin solution is introduced intermittently, by carefully opening and closing the stop-cock 3, the apparatus 55 being shaken after each addition. When the starch-iodo, blue color, persists for one-half minute, the end point in titration has been reached. The pink or violet color which appears in the solution must be distin- 60 guished from the starch-iodo blue which is the correct end point. Burette 5 is then again read. The apparatus is then emptied, rinsed with water and a blank test run to determine the amount of iodin solution 65 necessary to produce the permanent starch-

iodo blue color. In making this test, the same amount of starch solution and the same volume of water as is used in the determination, is again used, and the whole acidified with hydro-chlorid acid. From 70 the amount of gas and the volume of iodin solution used in the determination and in the blank, the number of grains of hydrogen sulfid per 100 cubic feet of gas is calculated. For control work, the volume of 75 gas used need not be reduced to its corresponding volume at standard conditions of temperature and pressure.

The uniformly higher results obtained by the gravimetric method may be due to the 80 absorption of sulfur compounds other than hydrogen sulfid, a much larger volume of gas and cadmium chlorid solution being used in the gravimetric method than in the volumetric method.

The principal advantage of Tutwiler's method is its rapidity. A test can be made in about three minutes. Its chief disadvantage is its inaccuracy. The results obtained are only approximate, especially on 90 the partially purified gas, the error varying from 1000 to 4000 per cent., as shown by the comparative tests above. This error is due to the titration of the gas with the iodin solution, the unsaturated hydro-carbons, 95 cyclopentadiene and probably sulfur compounds other than hydrogen sulfid reacting with the iodin. Results on the crude gas are less inaccurate, the error amounting to about fifteen per cent. This is, of course, 100 due to the much greater ratio between the amount of hydrogen sulfid present and the other compounds with which the iodin reacts. McMiller states in the original publication of Tutwiler's method that fifteen, 105 grains of hydrogen sulfid per 100 cubic feet of gas could escape detection. In the writer's experiments, in no case did the Tutwiler show less than ten grains per 100 cubic feet on clean coal gas nor less than 110 four grains per 100 cubic feet on clean water gas.

The gravimetric cadmium chlorid method is the most accurate in use at the present time. The great objection to this method, 115 however, in control work, is the length of time required to make a determination. The purifying boxes foul quite rapidly and in determining their efficiency, tests should be made rapidly and as nearly simultaneously 120 at inlet and outlet of purifier, as possible. A method which requires hours for a test becomes impracticable. The large bulk of cadmium chlorid solution used allows absorption of other sulfur compounds than 125 hydrogen sulfid, which, when oxidized with the bromin, give too high results. Another objection is the large amount of cadmium sulfid precipitate required to produce an amount of barium sulfate which can be 130

readily and accurately weighed. When a sample of 0.1 cubic foot of gas is taken, each milligram of BaSO_4 is equivalent to 146 gram of sulfur per 100 100 cubic feet. Thus, for partially purified gas containing but a fraction of one grain of hydrogen sulfid per 100 cubic feet, a number of cubic feet of gas must be used in order to obtain a weighable precipitate.

10 The volumetric cadmium chlorid method has several advantages over the gravimetric method. Accurate results are obtained on a much smaller volume of gas; a smaller volume of cadmium chlorid solution causes less absorption of sulfur compounds other than hydrogen sulfid; the method is much more rapid, requiring for a determination instead of hours, from seven to ten minutes, depending upon the purity of the gas.

20 While in the Tutwiler method, the titration is made under diminished pressure and out of contact with air, it is made in the presence of all of the other constituents of the gas, to-wit, unsaturated hydrocarbon 25 mercaptans hydrocyanic acid, cyclopentadiene, etc. With my improved apparatus and in accordance with the improved process, the titration is not only made under diminished pressure and out of contact with air, 30 but provides means of making the titration out of contact with the other constituents of the gas, and which constituents will not affect the iodin solution. This is a highly important improvement over the said Tutwiler method.

35 The advantages of the volumetric cadmium chlorid method over the Tutwiler are several. Twenty-eight times as much gas is used in the average determination as is used in the Tutwiler; the burette readings are one-tenth those of the Tutwiler and much more accurate results on gas of low hydrogen sulfid content are obtained. A test can be made in from seven to ten minutes.

40 45 What I claim is:

1. A gas testing apparatus comprising a main bulb having an upwardly extended tube and two burettes connected to the upper end thereof, a valve for closing the lower ends of said burettes and for connecting the same, at will, to said tube, a valved tube extending into said main bulb and downward within the same, and another valved tube

extending from the upper portion of said main bulb.

55 2. A gas testing apparatus comprising a main bulb having an upwardly extended tube and two burettes connected to the upper end thereof, a valve for closing the lower ends of said burettes and for connecting the same, at will, to said tube, a valved tube extending into said main bulb and downward within the same, and another valved tube extending from the upper portion of said main bulb and provided with a U-shaped downward bend adapted to serve as a seal.

60 3. A gas testing apparatus comprising a main bulb having an upwardly extended tube and two burettes connected to the upper end thereof, a valve for closing the lower ends of said burettes and for connecting the same, at will, to said tube, a valved tube extending into said main bulb and downward within the same, and another valved tube extending from the upper portion of said main bulb and provided with a bulb that is 70 75 small as compared with said main bulb.

75 4. A gas testing apparatus comprising a main bulb having an upwardly extended tube and two burettes connected to the upper end thereof, a valve for closing the lower ends of said burettes and for connecting the same, at will, to said tube, a valved tube extending into said main bulb and downward within the same, and another valved tube extending from the upper portion of said main bulb and provided with a U-shaped downward depression and a bulb, which bulb is small as compared with said main bulb.

80 85 5. The process of determining the amount of hydrogen sulfid in coal gas or other gas containing the same, which consists, in absorbing the hydrogen sulfid content and allowing the other constituents of the gas to escape, in confining the absorbed hydrogen sulfid gas, and in liberating the said hydrogen sulfid gas, by the use of hydrochloric acid in a partial vacuum, and in titrating under partial vacuum.

90 95 In testimony whereof I affix my signature 100 in presence of two witnesses.

EINER JOHNSON.
